UNITED STATES PATENT OFFICE.

CHARLES D. DALLAS, OF WINNETKA, ILLINOIS.

TUBE-CLEANING APPARATUS FOR TINNING PURPOSES.

Application filed October 21, 1922. Serial No. 595,996.

My invention relates to an improvement in tinning mechanisms, and more particularly to provide such a mechanism wherein tubing or the like that is to be tinned may be worked on continuously, that is, the process shall be substantially endless wherein a tubing of any desired length may be run through the tinning mechanism as it comes from the forming machine and wherein the advancing portion of the tubing is first coated and cleaned with acid, then passed into the tinning bath and next passed through a cooling medium, all of the successive operations going on simultaneously upon the adjacent portions of the constantly advancing tubing.

The invention has among its other objects the production of a device of the kind described which is simple, convenient, compact, durable, reliable, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a front elevation of my device;

Fig. 2 is a section taken on the line 2—2 of Fig. 3;

Fig. 3 is a section taken on the line 3—3 of Fig. 2;

Fig. 4 is a section through the tinning bath;

Fig. 5 is a section taken on the line 5—5 of Fig. 4;

Fig. 6 is a section taken on the line 6—6 of Fig. 4;

Fig. 7 is a section taken on the line 7—7 of Fig. 4;

Fig. 8 is a section taken on the line 8—8 of Fig. 4;

Fig. 9 is a section through the cooling bath;

Fig. 10 is a section taken on the line 10—10 of Fig. 9;

Fig. 11 is a section taken on the line 11—11 of Fig. 9.

In the drawings, wherein I have illustrated the preferred embodiment of my in-

vention, there is shown means for successively applying acid, tinning and cooling a constantly advancing continuous length of tubing 1, said means being indicated at 2, 60 3 and 4 respectively.

The acid-applying means 2 is made up preferably of a pair of absorbent members, 5—5, (see Figs. 2 and 3) preferably movable relative to each other as shown to and from each other and provided with an opening 6 therethrough, engageable with the tubing and through which the tubing must pass. The members 5—5 are controlled in their movement to and from one another by any suitable means, as for instance the gear means 7—7, having links 8—8 connected to said members 5—5. The links 8—8 shown in Figs. 2 and 3 are fixed to the shafts upon which they are mounted, and said shafts are supported in bearings, as shown. Each shaft carries a gear wheel 7, the two gear wheels intermeshing so as to operate together and cause the said shafts and links to also operate simultaneously. A lever A is secured to one of the gear wheels 7, as illustrated, in any preferred manner, by means of which the gears are slightly rotated.

Each pair of links carries one member of the box which contains the absorbing material 5 through the center 6 of which the pipe to be tinned is guided. It will thus be seen by referring to Fig. 3 that a movement of the lever A to the left, as indicated by dotted lines, will cause the links and their connected parts to separate, opening up the passage 6 so that the pipe may be readily placed therein. When the pipe has been suitably positioned, manipulating the lever 8 and moving it to the right will cause the pairs of links with their associated parts to approach each other, closing the absorbent material snugly down upon the pipe. A container or reservoir 9 is carried above one of the members 5, and has openings 10 therethrough in communication with the material of the absorbent members to saturate them, so that when the tubing is passed therethrough it will be frictionally and slidably engaged by the absorbent members, and be cleaned with the acid.

The tinning bath 3 is arranged adjacent the acid applying means 2, so as to receive that portion of the tubing that has already passed through said acid-applying means. This tinning bath comprises a tank 11 having an inlet and an outlet opening 12 and

13, respectively, substantially at the normal level 14 of the soldering or liquid in the tank. A plug 15 may be removably inserted into the bottom of the tank to provide a drain therefor, and a heating pipe 16 may be arranged beneath the tank to keep the contents thereof at the desired temperature. I have also illustrated a temperature controlling device 16', which may be connected with the heating means so as to regulate the heat. This may be as desired and need not be described in detail.

Leading into and out of the tank 11 are tubular guides 17 and 18 respectively, said guides having their outer ends at a higher elevation than the normal level 14 of the liquid in the tank, and are inclined downwardly so as to be below said level of liquid at their inner ends, said inner ends of the guides preferably slightly spaced apart, as shown in Fig. 4. Openings 19 may be and are preferably provided through the walls of the guides 17 and 18 at spaced intervals, so that the contents of the tank may come in direct contact with the tubing passed through the guides. The guides are substantially of a larger internal diameter than the tubing passed therethrough, except at spaced intervals wherein are arranged bushings 20' having a bore substantially equal to the size of the tubing so as to center or guide and prevent the bending, crushing or distortion of the tubing, and also to serve for the purpose of partially restricting the flow of the tinning material longitudinally with the tubing. The end guide 18' may be provided with a renewable tip 18" if so desired. Thus it is seen that none of the tinning material will be spilled from the tank, nor carried out of the tank by the tubing.

The tubing as it comes from the hot tinning bath is very hot and must be cooled before it can be handled. The cooling means 45 4 is arranged adjacent the discharge side of the tinning bath and comprises a tube or sleeve 20, (Fig. 9) having openings 21 through its wall. A jacket 22 encircles the sleeve 20 and is radially spaced therefrom to provide an annular chamber therebetween said chamber having an inlet for the water connection 23.

The inlet end of the tube 20 is flared, as at 24, while the remainder of said tube is 55 of a diameter a little larger than the diameter of the tubing handled so that the cooling water may enter through the opening 21 and spray the tube. A tank 25 is preferably arranged beneath the water-applying parts so as to provide a drain therefor.

As shown in Fig. 1, all of said parts may 65 be situated at a convenient elevation for practical handling, by means of the suitable supports or tables 26. The tube when of the lock seam type is effectively sealed or sol-

dered by the bath, and is coated or turned, as it is termed, so that it may be very efficiently used in making up radiators or the like for automobiles, or for other uses.

From the foregoing description it will be seen that there is provided means for applying the acid, tin and cooling a continuous length of tubing without stopping or interrupting the advancing movement of the tubing as it comes from the forming machine and without any of the acid, tin, or water reaching the interior of the tubing. Consequently, the tubing may be efficiently tinned and rapidly handled at a low cost.

Having thus described my invention, it is obvious that various immaterial modifications may be made in the same without departing from the spirit of my invention; hence I do not wish to be understood as 85 limiting myself to the exact form, construction, arrangement and combination of parts herein shown and described or uses mentioned.

What I claim as new and desire to secure 90 by Letters Patent is:

1. A device for cleaning the exterior surface of tubing, comprising a pair of tubing engaging absorbent members, movable toward one another and provided with a channel through which the tubing is moved, a container carrying one of said absorbent members and provided with openings through its bottom wall leading to said absorbent material, links for pivotally mounting said 100 container and the other of said absorbent members to a stationary part and means for controlling the movement of said links to move said members in suitably spaced relation.

2. In a device of the kind described, cleaning means comprising parallel shafts spaced from one another and rotatably supported, each shaft being provided with a gear wheel, the two intermeshing so as to cause the 110 shafts to rotate in unison, in combination with a pair of links fixedly mounted on each of the shafts, at their free ends carrying one member of a wiping box, and wiping material placed in each member of said box, whereby the wiping box may be adjusted as desired.

3. In a device of the kind described, cleaning mechanism comprising a box separable on a longitudinal line, and absorptive wiping material arranged in each part of the box, in combination with mechanism arranged to separate the sections and for moving the same in their relative positions.

4. Cleaning apparatus of the kind described comprising a pair of cooperating absorbent wiping members, and means for operatively supporting the same, in combination with mechanism for moving said members toward and from each other.

5. Cleaning apparatus of the character described comprising a pair of cooperating absorbent wiping members, means for operatively supporting the same and means for saturating one of said elements with a liquid, in combination with mechanism for moving said members toward and from each other.
6. Apparatus for cleaning tubing comprising a support, an element formed of absorbent material fixed to the support, a second element formed of absorbent material, and means for moving said second element toward and away from said first element.
7. Apparatus for cleaning tubing comprising a support, an element formed of absorbent material fixed to the support, a second element formed of absorbent material, means for moving said second element toward and away from first element, and means for saturating one of said elements with liquid.
8. Apparatus for cleaning tubing comprising a support, an element formed of absorbent material fixed to the support, links for pivotally mounting said second element, and a container movable with said second element and communicating therewith for supplying liquid thereto.
9. Apparatus for cleaning tubing comprising an element formed of absorbent material, means for movably mounting said element, and a container movable with said element and communicating therewith for supplying liquid thereto.
10. Apparatus for cleaning tubing comprising an element formed of absorbent material, a second element formed of absorbent material and movable relative to said first-mentioned element, and a container associated with one of said elements for saturating it with a liquid.

In testimony whereof, I have hereunto signed my name.

CHARLES D. DALLAS.
